UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

CLUTCH.

1,290,713.

Specification of Letters Patent.

Patented Jan. 7, 1919.

Application filed June 24, 1914. Serial No. 847,107.

To all whom it may concern:

Be it known that I, ELBERT H. CARROLL, a citizen of the United States, residing at Worcester, in the county of Worcester and 5 Commonwealth of Massachusetts, have invented a new and useful Improvement in Clutches, of which the following, taken in connection with the accompanying drawings, is a specification.

10 The present invention relates to a clutch, comprising a driving and a driven member, and means for frictionally connecting said members at will. In the embodiment thereof shown in the accompanying drawings, 15 and hereinafter described and claimed, my invention is applied to a rotatable wire drawing block and serves to connect the shell or winding surface of said block with its driving mechanism. However, my invention 20 is not limited to such a use, but is applicable to any and all uses wherein it is desired to transmit considerable power with the least possible shock to the mechanism in starting.

25 In the said drawings,

Figure 1 is a central vertical sectional view of a wire drawing block embodying my invention.

Fig. 2 is a sectional view on line 2—2, 30 Fig. 1.

Fig. 3 is a sectional view on line 3—3, Fig. 1.

Fig. 4 is a view similar to Fig. 3, showing the operating parts in a different position, 35 and

Fig. 5 is a view in elevation of the mechanism contained within the interior of the block, the shell being broken away to disclose the same.

40 Like reference characters refer to like parts in the different figures.

Referring to the drawings, 1 denotes a driving shaft, suitably journaled in a fixed bearing 2, and having secured to its lower 45 end a bevel gear 3, by means of which rotative movement, from a source of power, not shown, is constantly imparted to said shaft. The bearing 2 of said shaft is preferably carried by the table or framework of the 50 machine, and its upper end is adapted for the support of a substantially cup shaped member 4, forming an annular oil receptacle and having an inner annular overhanging lip or flange 5 which rests on the upper end of said bearing. Near its upper end the said 55 shaft 1 is squared, and a driving hub 6, having a central aperture corresponding in shape and size to the cross section of said shaft is slidably fitted thereon. A depending annular flange 7 of said hub enters an 60 annular recess 8 formed in the bottom of member 4 and rests upon an anti-friction ring 9 lying in the bottom of said recess. The hub 6 rotates with the shaft 1, and its rotation is adapted to be imparted to the 65 normally stationary member 4 and to the wire receiving surface of the block by the mechanism about to be described. The above referred to construction, relating to the support of the wire drawing block by the bearing 2, forms no part of the present invention, the same being described and claimed in the Letters Patent of the United States issued to me February 29, 1916, No. 1,173,707.

The member 4 has an outer upstanding 70 annular rim 10, provided at its base with a flange 11 which is adapted for the support of a shell 12, the periphery of which forms the winding surface of the block. The shell 12 has an internal recess 13 formed in its 75 side wall, within which fits a projection 14, on the rim 10 of the member 4, whereby said member and shell are connected together to rotate in unison. The shell 12 projects upwardly in surrounding relation to the member 4 and hub 6, and is provided with a 80 preferably integral cover section 15, spaced above said member and hub and having a central opening formed therein which is surrounded by a depending boss 16, through 85 which loosely extends the upper reduced portion of the shaft 1. A plate or disk 17, guided by said boss and capable of sliding movement with respect thereto, is constrained to move downwardly thereon by a 90 spring 18, surrounding said boss and housed within a recess 19 formed on the upper surface of said plate, against which the lower end of said spring bears. The plate 17 has a depending annular flange 20, the outside 95 diameter of which closely corresponds to the inside diameter of an annular upstanding flange 21 carried by the driving hub 6, in surrounding relation to the flange 20 on said plate. The contiguous faces of said 100 flanges are beveled, as shown, and constitute coöperating conical frictional clutching surfaces adapted to be rendered operative

105

2
by lowering the plate 17 so that said surfaces are brought into contact. The spring 18 serves to press the flange 20 into increasingly intimate contact with flange 21, effecting the rotation of the plate 17 in unison with the driving hub. The plate 17 is moved upwardly, against the force of spring 18, to disengage said clutching surfaces by posts 22, one of which is shown in Fig. 1, 10 said posts projecting upwardly from a ring 23 through holes formed in bosses 24 formed on the rim 10 of member 4. The ring 23, which surrounds the lower end of said member, is raised and lowered by operating arms 15 25, one of which is shown in Fig. 1, said arms being elevated to release the clutching members by any suitable manually operated mechanism, such, for example, as that shown and described in Letters Patent of the 20 United States No. 1,007,335, issued to me October 31, 1911.

A boss 26, formed on the interior of the rim 10 of member 4, has journaled therein a rocking stud 27, which is provided on its 25 upper end with a radial arm 28. The free end of arm 28 is so disposed as to contact with an irregular raised cam track 29 formed on the upper surface of plate 17. A second radial arm 30, at an acute angle to the arm 28 and spaced below the same, projects from the stud 27, the free end of said arm carrying a pivot pin 31, to the ends of which are pivotally attached, on opposite sides of the arm 30, the rearwardly extending curved 30 35 parallel links 32. Said links 32 are provided, near their free ends, with a plurality of sets of registering holes 33, by means of which the small end of a spiral spring or band 35, pivotally connected to said links 40 by a pin 34 inserted in said holes, may be adjusted with respect to said links. The band 35 is wound loosely around the driving hub 6, with its convolutions superposed one 45 upon the other, and its other end has an enlargement 36 which fits within a recess 37 in the interior of member 4.

The cover section 15 of the shell 12 has a curved upstanding rim 38 forming a shield, which is provided with an opening 39 50 through which a chain 40, or other suitable flexible connection, having a wire gripping mechanism, not shown, on its outer end, is drawn. A swinging lever 41 is journaled on a stud 42 projecting from the cover section 15, with its free end adapted to be connected to the inner end of chain 40. Attached to the lever between its free end and its pivotal point is a spring 43, which has its other end secured to a stud 44 on 55 said cover section, said spring exerting a tension to draw the lever 41 into the dotted line position, Fig. 2, when the strain of the wire upon the chain 40 is relieved. The lever 41 is held in the full line position 60 shown in Fig. 2 by means of a

latch 45 operating through an opening 46 in the cover section 15 to engage a shoulder 47 in the edge of said lever. The latch 45 is pivoted on a pin 48, carried by an enlargement 49 extending upwardly from the 70 rim 10 of member 4, and the latch is held in position to engage the shoulder 47 by a spring 50, attached at one end to the latch between its pivot and its free end, and at the other end to a stud 51 on the plate 17. 75

The spring 50 acts to retain a projection 52 on the inner edge of said latch against the periphery of the plate 17. The said periphery has a depression 53 within which, in the stationary condition of the mechanism, shown in Fig. 3, the projection 52 lies, thereby holding the free end of said latch 45 inwardly, in the path of the shoulder 47. Rotation of the plate 17 in the direction of arrow A, Fig. 3, causes the 85 free end of the latch to move outwardly, when said projection 52 rides upon the circular portion of the periphery of the plate.

In operation, with the parts in the positions shown in Figs. 2 and 3, the latch 45 holds the lever 41 in the full line position, Fig. 2, against the force of spring 43, with the flexible connection 40 extended beyond said shield to provide for the attaching of the wire thereto. When this is accomplished, the rotation of the mechanism is started by the withdrawal of the posts 22 from the support of plate 17, permitting the beveled face of the flange 20 of said plate to make frictional contact with the correspondingly beveled face of the flange 21 of the rotating driving hub 6, under the pressure of spring 18. The initial rotation of the plate 17 in the direction of arrow A, Fig. 3, as a consequence of the supplemental 100 frictional clutching action, above described, moves the end of latch 45 outwardly. This movement allows the flexible connection 40 to be withdrawn immediately within the rim 38 by the spring 43, in case the 105 strain of the wire upon said flexible connection 40 is released for any reason, thereby preventing liability of injury to the attendant, due to swinging of said connection by centrifugal force in the rotation of the block. During the movement of the plate 17 to effect the above described release of the lever 41 from the latch 45, the travel of the end of said arm 28 along the raised cam track 29 is not sufficient to cause any appreciable movement of said arm, owing to the substantially radial disposition of the inner portion of said track, indicated at 54, Figs. 3 and 4, which moves past the free end of the arm during 110 this time. Further rotation of said plate, however, brings the main section of the cam track 29 against the end of said arm, with the result that the arm is forced outwardly, 115 effecting the rocking of stud 27 to carry 120 125 130

the arm 30 in a direction to draw the band 35 tight upon the driving hub 6. As the band is drawn up upon said hub, the rotation of the latter is gradually imparted to 5 said band and from said band to the member 4 and the shell 12, by means of the interlocking projections and recesses 36, 37 and 14, 13 respectively.

In this manner the powerful driving force 10 of the shaft 1 is imparted, without shock, to the wire drawing block, through the medium of band 35, which is drawn tight upon the driving hub 6 by power furnished by the machine. The power necessary to 15 so tighten the band 35 is transmitted by means of the supplemental friction produced between the driving hub 6 and the plate 17; and by the arrangement of the cam track 29 and arm 28, the force which 20 is thus transmitted by the friction clutch between the hub 6 and plate 17 is greatly multiplied in order to insure the application of ample force to tighten the band 35. In other words, the plate 17 is caused to 25 rotate through a considerable arc to effect a very small movement of the small end of said band, and it will be apparent that the multiplying effect, above described, may be varied at will by changing the contour 30 of cam track 29 and the relative proportions of arms 28 and 30.

During the drawing operation, the shaft 1; member 4 and shell 12 rotate in unison, with the end of arm 28 bearing against 35 cam track 29, in a position farther or nearer the inner end of said track as determined by the tension of the wire in opposition to the rotation of the shell. When the drawing operation is completed, or when it is 40 desired to stop the mechanism, the plate 17 is raised by elevation of the ring 23, thereby eliminating the supplemental friction produced between the hub 6 and said plate. The operative connection between the hub 45 6 and the shell 12 is thereby destroyed and the rotation of said shell comes to an end because the elastic band 35 becomes loosened on said hub due to the resilience of the elastic band 35. The plate 17 is drawn 50 back into the position shown in Fig. 3, under the influence of the spring 50, causing the end of arm 28 to assume its former position on the portion 54 of the track and effecting the inward movement of latch 45 55 to hold the lever 41 in its full line position, Fig. 2. In order to prevent too great a recoil of the plate 17, a raised portion 55 is provided and is adapted to contact with the arm 28 and to guide it into contact with 60 the portion 54 of track 29, in readiness to move thereon when the clutching mechanism is again rendered operative. The return of the plate 17 to the position shown in Fig. 3 again causes the latch 45 to be interposed 65 in the path of lever 41, whereby the latter

is held in the full line position Fig. 2, in readiness for the attachment of the end of the wire to the flexible connection 40.

I claim,

1. A clutch having driving and driven members, an elastic band surrounding said driving member and having one end operatively connected with the driven member, means connected with the other end of said band for tightening the band around the 75 driving member, a movable member, and a cam carried by said movable member for actuating said tightening means.

2. A clutch having driving and driven members, an elastic band spirally surrounding said driving member, and operatively connected with the driven member, a movable member, means for forcing said movable member into frictional engagement with said driving member, an oscillating 80 stud supported by the driven member, levers of unequal length attached to said stud, with the shorter of said levers attached to one end of said elastic band, and a cam carried by said movable member for actuating 85 the longer of said levers to draw said elastic band into frictional contact with the driving member.

3. A clutch having driving and driven members, a member movable into frictional 95 engagement with said driving member, an elastic band surrounding said driving member and having one end operatively connected with said driven member, a rocking stud carrying two arms of unequal length, an 100 adjustable connection between the opposite end of said elastic band and the shorter of said arms, and a cam carried by said movable member in contact with said longer arm.

4. A clutch having driving and driven members, a member movable into frictional engagement with said driving member, an elastic band surrounding said driving member having one end in operative connection 110 with the driven member, a rocking stud carried by the driven member and having two radial arms, with one of said arms attached to the opposite end of said elastic band, a cam carried by said movable member and 115 actuating said second radial arm to tighten said elastic band on the driving member.

5. A clutch having driving and driven members, a band surrounding said driving member and attached at one end to said 120 driven member, a member movable into engagement with said driving member to rotate therewith, said member having a cam surface thereon, and a rocker arm carried by said driven member and operatively connected with the opposite end of said band, said arm bearing against said cam surface to transmit the movement of said movable member with multiplied power to the other end of said band.

6. In a clutch of the class described, a driving and a driven member, an elastic band encircling said driving member and connected with the driven member, a member movable into frictional engagement with said driving member, a swinging arm supported by the driven member and operatively connected with said elastic band to tighten the same on the driving member, a cam carried by said movable member to 10 actuate said swinging arm, and a stop to limit the movement of said arm in one direction.

7. In a clutch of the class described, a driving and a driven member, an elastic band encircling said driving member and

having one end operatively connected with said driven member, a swinging arm supported by the driven member and operatively connected with the opposite end of 20 said elastic band, a member movable into frictional engagement with said driving member, a cam carried by said movable member for actuating said swinging arm to tighten said elastic band, said cam having 25 an initial section radially disposed on said movable member.

Dated this 22nd day of June, 1914.

ELBERT H. CARROLL.
